(57) **CLAIM**

The ornamental design for a pet tracker attachment, as shown and described.

DESCRIPTION

FIG. 1 is a front perspective view of a pet tracker attachment in accordance with the disclosed subject matter.

FIG. 2 is a top view of the pet tracker attachment shown in FIG. 1.

FIG. 3 is a bottom view of the pet tracker attachment shown in FIG. 1.

FIG. 4 is a right side view of the pet tracker attachment shown in FIG. 1.

FIG. 5 is a left side view of the pet tracker attachment shown in FIG. 1.

FIG. 6 is a front plan view of the pet tracker attachment shown in FIG. 1.

FIG. 7 is a back plan view of the pet tracker attachment shown in FIG. 1; and,

FIG. 8 is a front perspective view of the pet tracker attachment shown in FIG. 1, in an environment of use shown as coupled with a collar band and worn on a canine as depicted by broken lines.

The broken lines showing the pet tracker, collar, and canine in FIG. 8 are included solely for the purpose of illustrating environmental structure, while all other broken lines illustrate portions of the pet tracker attachment; the broken lines throughout the figures form no part of the claimed design.
